UNITED STATES PATENT OFFICE

106,823

DESIGN FOR A HEARING AID AMPLIFIER CASING

Sterling G. Sears, Garden City, N. Y., assignor to
Dictograph Products Company, Inc., New York,
N. Y., a corporation of Delaware

Application June 10, 1937, Serial No. 69,774

Term of patent 7 years

To all whom it may concern:

Be it known that I, Sterling G. Sears, a citizen of the United States, residing at Garden City, county of Nassau, State of New York, have invented a new, original, and ornamental Design for a Hearing Aid Amplifier Casing, of which the following is a specification, reference being had to the accompanying drawing, forming a part thereof, in which;

Figure 1 is an elevation of the hearing-aid amplifier casing showing the new design;

Fig. 2 is an end view thereof; and,

Fig. 3 is a plan view thereof.

I claim:

The ornamental design for a hearing aid amplifier casing, as shown.

STERLING G. SEARS,
